UNITED STATES PATENT OFFICE

2,438,770

ADJUSTABLE MUTUAL COUPLING

John E. Tillman, Stratford, Conn., assignor to
General Electric Company, a corporation of
New York

Application June 5, 1943, Serial No. 489,803

10 Claims. (Cl. 171—777)

1

My invention relates to coupling apparatus for radio receivers and similar communication circuits. It is an object of my invention to provide an improved coupling arrangement for the high frequency transformers used in such circuits.

My invention relates more particularly to powdered iron transformers such as are customarily used in the intermediate frequency stages of a superheterodyne radio receiver. It is another object of my invention to provide an improved means for adjusting the mutual coupling of the windings of such a transformer.

Still another object of my invention is to provide an improved transformer in which the mutual coupling may be easily and accurately adjusted over a wide range of values.

One of the features of my invention is the linking of a pair of windings carrying high frequency currents and separated by a common wall having a movable core so that the mutual coupling of the windings may be adjusted by varying the position of this core in the common wall.

A further object of my invention, therefore, is to provide an improved radio frequency transformer in which the reluctance of the common magnetic path of the transformer windings may be varied easily and accurately by a single adjusting operation.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing, in which Fig. 1 is a side elevation view, partly in section, of a transformer embodying my invention; Fig. 2 is a plan view of the transformer of Fig. 1 along the line 2—2; Fig. 3 is a side elevation view, partly in section, of a modification of the transformer of Fig. 1; and Fig. 4 is a plan view of the transformer of Fig. 3.

Referring to Fig. 1, I have shown a radio frequency transformer having a main body member 10. The body member 10, preferably, is formed as a unitary structure by molding or compressing a mass comprising powdered iron particles and then machining as required. The member 10 has a pair of recesses, or cups, 11 and 11', these recesses preferably being substantially cylindrical in shape and separated by a common wall 12 through which is bored a centrally located cylindrical hole 12'. Two end walls 13, 14 and a base portion 15 complete the structure of the body member 10.

The base member 15 has a pair of shouldered recesses 17, 18 for receiving the lower ends of tubular forms 19, 20, upon which are wound the transformer windings 21, 22. The forms 19, 20

preferably are of insulating material of a synthetic resin type, although any other suitable dielectric material may be used. The open ends of the recesses are provided with a closure member

5 24 having a central opening corresponding to the hole 12' in the body member and the pair of openings through which the tubular forms 19, 20 may pass. The closure member 24 is likewise provided with a plurality of shoulders 26 to fit securely about the walls 12, 13, 14 forming the sides of the recesses 11, 11'. Apertures 27 are provided in the closure member 24 and leads 30 of the windings may be threaded through these apertures for connecting the windings to their associated circuits. A casing 28 of any suitable material, such as a molded phenolic resin, is used to enclose the entire transformer structure. A pair of threaded studs 29 are provided to extend through corresponding holes in the closure member 24, body member 10 and casing 28, to secure the closure member to the body member by means of nuts 39.

Means for adjusting the inductance of the coils of windings 21, 22 to a desired value is provided 25 by the powdered iron cores 31, 32 adjustably disposed within the forms 19 and 20. Embedded in the iron cores, or tuning slugs, 31, 32 are threaded members 33 provided with slots 34 at their upper ends so that, by means of these slots 34, the position of the cores within the windings of the transformer may be adjusted in a manner to be explained later.

The transformer body 10 may be supported 35 from a radio chassis 38 by means of the bolts 29. An insulating board 37 is secured to the chassis in any desirable manner. The heads 38 of the bolts 29 are supported from the chassis 36 and are held in position by means of a nut 39 and the lock washer 40. Nuts 41, riveted to 40 mounting board 37 in a well-known manner, provide means for threadedly engaging screws 33 having one of their ends embedded in the tuning cores 31, 32 so that, by means of the slots 34, these cores may be raised or lowered within the windings of the transformer, tuning the windings in the usual manner.

In order to provide means to adjust the mutual coupling of the windings 21, 22 of the transformer, a core member 44, comprising the circular powdered iron bodies 45, 46 secured in spaced relation to a threaded screw 47, is located in the circular opening 12' in the common wall 12 between the recesses 11, 11'. The screw 47 is provided with a slot 48 at its upper end and engages a nut 49 soldered to the chassis.

The operation of the transformer described will be discussed with particular reference to its use as an intermediate frequency transformer in a radio receiver of the superheterodyne type. In Fig. 1, there are shown two dotted paths A and

B to designate the paths of flux lines in the transformer housing. The flux lines A, which for winding 21 flow from the core member 24 through the closure member 24 to the side wall 13 and the center wall 12, are the normal lines for the member 24 and are confined to the core 31 and the adjacent half of housing 10. The number of flux lines A for a given transformer winding is determined by the position of the tuning cores 31, 32. Adjustment of the position of these cores with respect to their corresponding windings is effective to vary the self-inductance of the coils 21, 22 until desired values of inductance for these coils are obtained.

The flux lines B are those lines of flux which return to the core 31 through the core 32, rather than the walls of the housing, and form a common linkage or coupling of the windings 21, 22. The mutual coupling of the windings 21, 22, therefore, is determined primarily by the reluctance of the path across the common wall 12 and through the cores 31, 32. If the reluctance of this path is increased, the proportion of the flux lines B in relation to the number of flux lines A is decreased, the number of lines of flux flowing through the path A remaining essentially the same. In the transformer of Fig. 1, the reluctance of the path B is controlled by means of the central core member 44 comprising the powdered iron body members 45 and 46. These members are in spaced relation so that an air gap is formed between them. When the core member 44 is in the position shown in Fig. 1, the reluctance of the path B is a minimum. When the body members of core member 44, however, are raised by adjustment of the screw 47 to a position such that the lower edge of member 45 is higher than the upper surface of member 24 and member 46 is at the mid-position of opening 12' so that there is an air gap at the centers of both base member 15 and closure member 24, the reluctance of the path B is a maximum. In the manufacture of a radio receiver, the position of tuning core 44 is adjusted by means of the slot 48, as by a screw driver, until the desired mutual coupling is obtained. Since the position of the core 44 does not affect, to any substantial amount, the reluctance of the paths for the normal lines of flux A of the windings 21, 22, the above adjustment of the mutual inductance of the windings 21, 22 is obtained with substantially no change in the self-inductance of these windings.

After adjustment of the position of the core 44 to secure the desired mutual inductance is determined, the recesses 11, 11', and 12' may be filled with any suitable sealing material, such as wax for holding the transformer winding and the mutual inductance tuning core 44 securely in place. Any further adjustment of the frequency of the transformers is made thereafter by adjustment of the iron cores 31, 32 with respect to the windings of the transformer to tune these windings to exact resonance with the capacitance of the associated circuits at a desired frequency.

In the construction of the main body 10, the tuning cores 31, 32, 44 and the closure member 24, which also functions as pole pieces for cores 31, 32, it is preferable to use powdered iron particles having low resistance and high conductance. Better electrostatic shielding is obtained if the particles are uninsulated from each other and are compressed, or otherwise molded, by any suitable method known in the art.

In the plan view of Fig. 2, is shown the upper

surface of the transformer of Fig. 1. This view points out more clearly the relative positions of tuning cores 31 and 32, the mutual inductance adjusting core 45, and the bolts 29 which support the transformer body from the chassis.

In the transformer arrangement shown in Fig. 3, the body member 50 is provided with two recesses, or cups, 51, 52, end walls 53, 54, a center wall 55, and a bottom portion 56. The coil forms 57 and 58, about which are placed the windings 59 and 60, are supported in the recesses 51, 52 in a manner similar to that described in connection with the transformer of Fig. 1. The recesses 51 and 52 are provided with shoulders 61 and 62 at their upper ends to receive individual closure members 63, 64 of metallic material.

The common wall 55 between recesses 51 and 52 is provided with an opening 66 which extends about two-thirds of the way through this common wall. A variable core 67 for adjusting the mutual coupling of the coils of the transformer is located within the opening 66 and its position within that opening may be varied by means of the screw 68 having its lower end embedded in the tuning core. A mounting board, similar to the mounting board 37 shown in the arrangement of Fig. 1, may be used in conjunction with the transformer of Fig. 3 for supporting the tuning core 67, by means of screw 68, and the cores 51 and 58, by means of screws 69, 70. The transformer as a whole may be supported from such a mounting board by means of bolts 71.

In this form of my transformer arrangement, adjustment of the position of tuning core 67 is effective to introduce a gap in only one side of the mutual inductance path between windings 59, 60 across the common wall 55. This arrangement is especially desirable where a limited amount of space is available for vertical movement of the tuning core 67. The principle of operation, however, is essentially the same as that described in conjunction with the transformer arrangement of Fig. 1. The essential features of this operation are the establishment of a common wall between windings of a transformer and controlling the reluctance of the mutual flux path through this common wall. While I have shown this as being done by means of the introduction of an air gap in this path, it is, of course, obvious that introduction of any type of non-magnetic material in this path is effective to control the mutual coupling of the winding.

Fig. 4 is a plan view of the transformer arrangement of Fig. 3, which shows with greater clarity the relative positions of tuning cores 51 and 58, the screw 63 for securing vertical movement of mutual inductance adjusting core 67, and the bolts 71 which support the transformer from the radio chassis. A casing similar to the casing 28 shown in Figs. 1 and 2 may be used with this transformer arrangement also, if desired.

While I have shown a particular embodiment of my invention, therefore, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. A radio frequency transformer comprising a body member of magnetic material having a

plurality of recesses therein, each of said recesses having a corresponding winding of said transformer positioned therein, said windings being tuned to a desired band of frequencies, a magnetic closure member for said recesses, said recesses being completely encircled by said magnetic material and being separated by a wall of said body member, said wall being included in the common magnetic path of said windings, and means whereby the reluctance of a portion of said wall may be varied to adjust the coupling between different of said windings to control the width of said band of frequencies.

2. A radio frequency transformer comprising a body member of magnetic material having a plurality of recesses therein, said recesses being completely encircled by said magnetic material and being separated by a wall of said member, said wall having an air-gap therein, each of said recesses having a corresponding winding of said transformer positioned therein, said windings being tuned to a desired band of frequencies, and magnetic closure members for said recesses, said windings producing flux traversing a path comprising said closure members and said wall, and the position of said gap in said wall being variable to vary the reluctance of said flux path and the mutual inductance of said windings to control the width of said band of frequencies.

3. A radio frequency transformer comprising a body member of magnetic material having a plurality of recesses therein, each of said recesses being completely encircled by said magnetic material and having a corresponding winding of said transformer positioned therein and tuned to a desired frequency, a magnetic closure member for said recesses, said recesses being separated by a wall of said body member, said wall having an air-gap therein, said gap being included in the common magnetic path of said windings, and a core member located in said gap, said core member being variable in position to vary the coupling between a pair of said windings while maintaining the tuning of said windings.

4. In a radio frequency transformer the combination of, a magnetic body member, a pair of windings magnetically associated therewith, said windings being completely surrounded by said body member and being separated by a wall of said body member, said wall being included in the common magnetic path of said windings, and means whereby the magnetic reluctance of said wall may be varied to vary the flux flowing through said path and the coupling between said windings while maintaining substantially constant the tuning of said windings.

5. A transformer for radio frequency currents comprising a magnetic body member, said body member having a pair of chambers therein separated by a wall of said body member, each of said chambers being substantially completely surrounded by said member and having a corresponding winding of said transformer positioned therein, a magnetic closure member for said chambers, said windings producing flux traversing a path comprising said closure member and said wall, said wall having a recess therein, and a core member supported in said recess, the position of said core member in said recess being variable to vary the reluctance of said flux path and the mutual inductance of said windings.

6. In a radio frequency transformer, the combination of a magnetic body member having a

pair of chambers therein, said chambers being completely surrounded by said body member and being separated by a wall of said member, a winding disposed in each of said chambers tuned to a desired resonance frequency, means for impressing an input voltage across one of said windings to produce flux traversing said wall to provide a desired output voltage across the other of said windings over a band of frequencies, means for varying the reluctance of a part of said wall to vary the flux traversing said wall and the width of said band, and means for adjusting the tuning of said windings individually to compensate for changes in the tuning thereof introduced by said variation of reluctance.

7. A radio frequency transformer comprising three parallel legs of magnetic material, a pair of transverse magnetic yokes connecting said legs, a pair of windings encircling respectively the outer two of said legs, means for varying the reluctance of said outer legs to vary the self-inductance of said windings, the other of said legs having an aperture therein, and means to vary the reluctance of the other of said legs to vary the mutual inductance of said windings comprising means for varying the dimensions of said aperture.

8. A radio frequency transformer comprising three parallel legs of magnetic material, a pair of transverse magnetic yokes connecting said legs, a pair of windings encircling respectively the outer two of said legs, means for varying the position of said outer legs with respect to said yokes to vary the self-inductance of said windings, the other of said legs having a gap therein, and means to vary the reluctance of the other of said legs to vary the mutual inductance of said windings comprising means for varying the position of said gap.

9. A radio frequency transformer comprising three parallel legs of magnetic material, a pair of transverse magnetic yokes connecting said legs, a pair of windings encircling respectively the outer two of said legs, means for varying the reluctance of said outer legs to vary the self-inductance of said windings, the other of said legs comprising a core member movable in a direction parallel with said legs and between said yokes whereby the mutual inductance of said windings may be varied.

10. A radio frequency transformer comprising five parallel legs of magnetic material, a pair of transverse magnetic yokes connecting said legs, the outer of said legs being fixed relative to said yokes, a pair of windings encircling respectively each of the legs adjacent said outer legs, said adjacent legs being movable in a direction transverse to said yokes to vary the self-inductance of said windings, and the remaining one of said legs being movable in a direction transverse to said yokes to vary the mutual inductance of said windings.
